RIBBON HOLDING DEVICE AND THE LIKE

Charles Gross, Englewood, N. J.

Application March 15, 1951, Serial No. 215,683

1 Claim. (Cl. 206—51)

1

The present invention relates to a ribbon package and it particularly relates to a device for forming a ribbon package.

Although not limited thereto the present invention will be particularly described in its application to ribbon attachment although it has a broader application to the packaging, holding, and display of various types of folded, coiled or hanked materials, whether of paper, tissue, plastic strips, yarns or the like.

It is among the objects of the present invention to provide a simple, inexpensive device by which ribbon or similar stripped materials, or even yarns, may be packaged in the form of flattened coils, windups, strands or hanks, and which will permit such ribbons and the like to be conveniently merchandised and retained in such packages while displaying the same during shipment, storage, merchandising, and even during utilization or consumption.

Another object of the present invention is to provide a hank holder for ribbons and the like which may be conveniently cut out of relatively thin paper and which will give assurance of a lasting permanent package adjustable to different sizes and which will not readily become undone during shipment, storage, merchandising and handling even though it may be relatively simply put up with a minimum of manual operations.

A further object is to provide a ribbon packaging system in which the hank of ribbon may be readily laid upon a relatively flat cutout and then locked in position by relatively simple manipulation without the need of wires or permanent fasteners, and with assurance that the ribbon will be properly displayed for inspection and sale.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

In accomplishing the above objects, it has been found most suitable to provide a base member upon which the flattened hank of ribbon, coil of yarn or other flattened windup of strip or thread materials may be positioned.

Extending from the top or bottom of the space is desirably a wrap-around tongue having extensions on the end thereof which, when wrapped

around the coil of ribbon or yarn, may be locked back in position on the base member.

The base member is desirably provided with upstanding oblique locking edges which will permit the outstanding end locking projections on the tongue to be engaged therewith, and the tendency to expand of the ribbon hank, yarn coil or the like will cause a locking between the projections of the tongue and the oblique edges of the base member.

In a preferred form, an elongated base is provided to provide a back for the entire length of the hank of yarn. This base has recesses at one side adjacent the ends of the position of the hank and has outstanding tongues from the other side.

These tongues are designed to wrap around the ribbon hank or coil of yarn, and then to engage the other side of the base so as to lock the ribbon in position.

In another form of the invention, the tongue with the base may just engage the central portion of the hank of ribbon or coil of yarn and lock thereon after being wrapped around the same.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claim hereunto appended.

In the drawings where like reference characters denote corresponding parts throughout the several views:

Fig. 1 is a side plan view of a ribbon package according to one embodiment of the present invention, showing a hank of yarn in position thereon and with the interlocking tongues in locked position.

Fig. 2 is a plan view of the wrapper or paper base with the outstanding tongues before application to the hank of ribbon, as shown in Fig. 1.

Fig. 3 is a transverse vertical sectional view upon the line 3—3 of Fig. 1 upon a slightly enlarged scale as compared to Fig. 1.

Fig. 4 is a fragmentary longitudinal sectional view upon the line 4—4 of Fig. 1 upon a slightly enlarged scale as compared to Fig. 3.

Fig. 5 is a fragmentary end view similar to one of the designs of Fig. 1, showing an alternative locking position of the tongue.

Fig. 6 is a front elevational view of an al-

ternative form of package where the wrap-around device of the present invention is applied solely to the middle portion of the hank of ribbon or coil of yarn or the like.

Fig. 7 is a plan view of the cutout or paper base and tongue combination removed from or before application to the package of Fig. 6.

Fig. 8 is a transverse vertical sectional view upon the line 8-8 of Fig. 6 upon a reduced scale as compared to Fig. 6.

Fig. 9 is a front elevational view of an alternative form of ribbon package similar to Fig. 6, showing the tongue already wrapped around the hank of ribbon, coil of yarn or the like.

Fig. 10 is a plan view of the paper or flexible wrap around used in the package of Fig. 9 before or after application to the hank of ribbon or coil of yarn, as the case may be.

Fig. 11 is a front plan view of an alternative form of ribbon package with the hank of ribbon already in locked position with only a single wrap around tongue as contrasted to the double tongue arrangements of Figs. 1 to 4.

Fig. 12 is a plan view of the paper base and tongue member as shown in wrapped position in Fig. 11 before application to the package of Fig. 11.

Referring to Figs. 1 to 4, there is shown a paper base A having the wrap around tongues B, for engaging the hank of ribbon C, the tongues having adjustable locking projections D.

Also the base and tongue structure, as shown in Figs. 1 and 2, is desirably of a heavy stock paper, it is apparent that it may also be made of plastic sheets or even of thin flexible metal sheets. Paper stock however is preferred.

Referring to Fig. 2, there is a base section 10 which is provided with a lower extension 11 and an upper extension 12. The central section 10 is connected to the enlarged end portions 13 by the portions 14. The recesses 15 between the central portion 10 and the end portions 13 provide a place where the tongues may be wrapped around the hank of ribbon C.

The oblique edges 16 on the outside of the side edges 17 of the tongues B, and the oblique edges 18 on the side edges 19 of the tongues B serve to engage the locking projections D.

As shown in Fig. 2, the locking projections D consist of the upper projections 20 on the inside and 21 on the outside, and the lower projections 22 on the inside and 23 on the outside. These projections are separated by the slits 24 and 25.

Although in Figs. 1, 3 and 4 there is shown a hank of ribbon C, it is obvious there may also be a strip of cellophane wrapping material, a coil of tinsel or even a coil of yarn or wire. Normally, this hank of material will be positioned as shown upon a central section 18, the bridges 14 and the enlarged portion 13.

Then the tongues B will be wrapped downwardly over the front of the hank C as indicated at E in Fig. 1, and the tongues will then be brought up to the back of the base structure A and the projections moved in front of the oblique edges 16 and 18 so as to form the lock as shown in Fig. 1, at the positions F and G.

The tendency of the hank of ribbon to expand will hold the tongues D tightly in position in engagement with the oblique edges 16 and 18.

It will be noted in the position shown in Fig. 1 all locking projections 20, 21, 22 and 23 are engaged in front of the oblique edges 16 and 18.

Where the coil or hank of ribbon C is heavier, as indicated in Fig. 5, and takes the form as indicated at H, only one of the tongues 20 and 21 may be positioned in front of and engaging the oblique edge 16 and 18, with the other tongues 22 and 23 being on the rear side of the base structure A.

The packaging, as shown in Figs. 1, 3, 4 and 5 may be readily applied after the coil of ribbon C is positioned thereon, and after the locking projections D of the tongues B have been applied either in the position as shown in Fig. 1 or in the position as shown in Fig. 5. They will remain substantially permanent throughout shipment, merchandising, storage, display and examination.

In the structure shown in Figs. 6 and 7, the base K is provided with a tongue L having the locking projections M. The base K has a slit recess as indicated at 30, to receive the wrap around of the tongue L, and it has the upstanding extensions 31 with the oblique locking edges 32.

The tongue M is provided with the lower locking projections 33 and the upper locking projections 34 separated by the slits 35. The splitting of the locking projections M gives the same adjustment as indicated in Figs. 1 and 5.

In the package shown in Fig. 6 the tongue L may be turned down as indicated at N and wrapped around the hank O of ribbon and then turned upwardly so that either one or both of the projections 33 and 34 are engaged with the oblique edges 32 of the upstanding portions 31. The wrapper as shown in Figs. 6 and 7 is relatively simple, involves a minimum of paper material and may be used for wrapping any desirable size of hank or coil.

The single locking projections as shown in Figs. 9 and 10 operates in the manner as already described in connection with Figs. 6, 7 and 8.

The base B has a tongue Q with the single locking projections R. The base P has the upstanding members 40 with the oblique edges 41 which engage the locking projections R in the manner shown in Fig. 9.

The tongue Q may be wrapped downwardly as indicated at S to engage the hank T, and then the locking projections may be snapped in front of the oblique locking edges 41, in the manner as indicated in Fig. 9.

In the structure shown in Figs. 11 and 12 the base U has a tongue V with the outstanding locking projections W. The central base member U has the enlarged wings X. The base U has a recess as indicated at 50 around which may be wrapped the side edges 51 of the tongue V. Then the tongue is turned up to the rear of the central section U and the locking projections W are snapped in front of the oblique edges 52. The final package, as shown in 11, differs from that shown in Figs. 6 and 9 in that the wings X give support to both sides of the ribbon hank Y.

It is thus apparent that the applicant has provided a simple ribbon package which may be readily formed from a die cut piece of heavy paper which may be replaced by metal or plastic if desired.

The double projections as shown at D and M in Figs. 2 and 7 have an adjustment, but where a definite size of ribbon is to be wrapped only a single locking projection as indicated at R in Fig. 10, or W in Fig. 12 need be provided.

As shown in Figs. 1 to 5 and 11 and 12, the hank of ribbon is supported throughout its

length on the backing card A or U—X. However, the unbacked structure as shown in Figs. 7 to 10 may also be employed.

As many changes could be made in the above ribbon holding devices and the like, and many widely different embodiments of this invention could be made without departing from the scope of the claim, it is intended that all matter contained in the above description shall be interpreted as illustrative and not in a limiting sense. 10

Having now particularly described and ascertained the nature of the invention, and in what manner the same is to be performed, what is claimed is:

A wrapper for ribbon hanks comprising an 15 elongated base having a rectangular enlarged central base portion and laterally and outwardly extending enlarged end wing portions with intermediate narrow bridges connecting said wing portions to the sides of the base portion and 20

upwardly extending elongated locking tongues, the inside and lower ends of which are integral with the bridges, extending transversely away from said bridge portions and having end slotted locking projections to wrap around the hank and engage the side edges of said base portion and said wing portions and to lock the ends of the tongues in wrapped-around position and to hold the hank in position.

CHARLES GROSS.
